UNITED STATES PATENT OFFICE.

JOSEPH A. LAWSON, OF MENANDS, NEW YORK.

REFERENCE-BOOK SHELF-DESK.

SPECIFICATION forming part of Letters Patent No. 752,234, dated February 16, 1904.

Application filed June 17, 1903. Serial No. 161,819. (No model.)

To all whom it may concern:

Be it known that I, JOSEPH A. LAWSON, a citizen of the United States, residing at Menands, in the county of Albany and State of New York, have invented new and useful Improvements in Book-Supports, of which the following is a specification.

My invention relates to book-supports for use with book-shelves of bookcases for temporarily receiving and supporting reference-books to be consulted; and it consists of the novel combinations of parts and devices hereinafter described, and set forth in the claim.

The object of this invention is to provide a portable book-support for use with book-shelves of bookcases in which a pair of parallel brackets embodying novel features of construction coöperate with a panel, also embodying novel features, for producing a portable book-support which will be adapted to be automatically secured to the narrow front margin of a book-shelf and retain a book placed thereon from sliding off and be readily detached therefrom for use on any other bookshelf in the bookcase. These improvements are clearly illustrated in the accompanying drawings, forming a part of the specification, in which—

Figure 1 is a horizontal view of my improved book-support applied to a book-shelf. Fig. 2 is a sectional elevation of the same, illustrating the novel features of the parts of the book-support for accomplishing the purpose of the same. Fig. 3 is a side view of one of the brackets of the same, showing novel features thereof; and Fig. 4 is a plan of the same.

Similar letters of reference refer to similar parts throughout the several views.

In the drawings is shown a bookcase of a type with which the book-support may be used; and in which A is the back wall of the same, B B are shelves for holding books of law and other publications frequently required to be consulted or referred to, and C C are volumes of such books in place on said shelves.

D is a suitable panel or board top, of rectangular form, which may be made of any suitable material, and preferably of wood of

any suitable kind or quality, and having its upper surfaces d even and smoothly finished, similar to a table-top. This panel may be made with any dimensions suitable to adapt the book-support for its intended use, whether in private library or in offices of professional men or in public offices, where books of reference are kept on book-shelves of cases provided for holding the same. This panel D has provided in its front edge margin two notches d' d' at suitable distances apart and made with a depth preferably of one-quarter of an inch or more inward from the front edge of said panel. In the rear edge margin of this panel are provided the two notches d'' d'' at same distance apart as notches d' d' and in alinement with the front edge margins d' d', for purpose hereinafter described. Secured on the upper side of this panel D and parallel with the front edge thereof and at a short distance back from notches d' d' is a bar D', extended, preferably, from end to end of said panel and serving as a stop-piece against which the lower end of a book may have bearing and thereby be prevented from sliding down and off from said panel when this book-support is in place attached to a book-shelf for use.

E E are two brackets which are arranged parallel to each other, as shown by full and dotted lines in Fig. 1, and are secured to the lower side of panel D by means provided at suitable distances apart for giving said panel a secure support. As these brackets E E are each a duplicate of the other, a description of one will suffice for that of the other. Bracket E is preferably made of cast metal and consists in part of body portion e, made in the form of a thin and narrow bar which widens as it is extended rearward for giving strength to said body portion and for strong connection with arms F and F', made integral with the same. Arm F is made integral with the rear end of body portion e of the bracket and is made horizontal in relation to inclined upper edge e' of the body portion e. This arm F is made with a short length for bearing on the upper side of the front edge margin of a bookshelf B without extending back so as to interfere with the books arranged on said shelf.

Arm F' is arranged below arm F and has a rearward extension from body portion e of greater length, preferably twice the length, than said upper arm for bearing against the 5 lower side of shelf B, on the upper side of which short arm F has bearing. These two arms F F' are each separated by opening E² of width about equal to the thickness of an ordinary book-shelf, which said opening receives when the bracket E is in place and holding with said shelf, as shown in Fig. 2. Made integral with the forward end of body portion e of the bracket is a holding-finger e³, which is projected upward above the plane of 15 top edge e⁵ of the bracket and is made with an angular form, as shown in Fig. 3, and provided with a small opening e⁸ for bearing on the upper side of the front margin of panel D after passing up through notches d' d' and 20 hold the latter from rising up from its bearing on the upper edge e⁵ of the bracket. Made integral with the body portion e of the bracket at a point about midway between said finger e³ and the projection e⁴, provided and extending 25 upward from the plane of edge e⁵, is the flange E', which is extended laterally from one side of the body portion e, with its upper surface on a plane with the upper edge e⁵ of the bracket, as shown in Figs. 3 and 4. This 30 flange is perforated for receiving a screw for securing said flange and the bracket it is connected with in place on panel D. These duplicate brackets are secured to panel D in manner shown, in which the brackets are arranged 35 parallel with each other against the lower side of said panel, with the lower portion of fingers e³ entered into notches d' d' in the front edge margin of the panel and the rearward extended upper portions of said finger 40 having bearing on the substance of the panel just rearward of said notches d', while the rearward projections e⁴ are entered into notches d² d² in the rear edge margin of panel D for their reception, when the brackets will be secured to 45 the lower side of the panel by suitable screws d³, passed through the perforation in flange E' and screwed into the panel from its lower side. When the brackets E E have been secured in place, with said panel itself held in 50 place from shifting laterally by its notches d' d' holding with fingers e³, with the upper portion of the said fingers bearing on the substance of the panel adjoining the said notches,

and with projections e⁴ holding with notches d² d² in the upper edge margin of the panel, 55 the two screws d³ will bind the two brackets in place, and the book-support thus produced will be strong, light in weight, and adapted to be automatically attached to the front margin of a book-shelf and be securely held with 60 the same by the joint action of arms F and F' with the respective sides of shelf B and the weight of the body portions of the brackets and the panel D without least liability of interference of the arms of the brackets with either 65 the placement of books on the shelf or removal of the same therefrom.

To prevent the metal of arms F and F' from marring either side of book-shelves this support may be used with, I secure on the outer 70 end portions of said arms pieces d⁴, of rubber, made, preferably, of rubber tubing, which prevent the metal of said arms from biting into the wood of the shelf.

The bar D', secured in place to the upper 75 side of panel D at a short distance from its lower edge and extending from end to end of said inclined panel, operates to hold a book placed on said inclined panel from sliding down and off from the same. 80

Having described my invention, what I claim is—

In a book-support, the combination with panel D provided in its forward edge margin with notches d' d' and in its rear edge margin 85 with notches d² d² in alinement with the forward-edge-margin notches, and bar D' secured parallel to the front edge margin of said panel, of brackets E E secured to the lower side of said panel, and each having integral with its 90 body e short upper arm F, for bearing on the front upper margin of a book-shelf, and long arm F' for bearing against the lower side of same shelf, and with fingers e³ holding with notches d' d' and bearing on a portion of material of said panel adjoining said notches and projections e⁴ holding with notches d² d² and having each flange E', perforated and projecting from a side of the body portion of each bracket and secured by a screw to the lower 100 side of said panel.

JOSEPH A. LAWSON.
